United States Patent Office.

H. C. ALEXANDER, OF NEW YORK, N. Y.

Letters Patent No. 98,007, dated December 21, 1869.

TOY-VELOCIPED.

The Schedule referred to in these Letters Patent and making part of the same.

To all whom it may concern:

Be it known that I, H. C. ALEXANDER, of the city, county, and State of New York, have invented a new and useful Improvement in Toy-Velocipedes; and I do hereby declare that the following is a full, clear, and exact description thereof, which will enable others skilled in the art to make and use the same, reference being had to the accompanying drawings, forming part of this specification, in which—

Figure 1 is a perspective view of my improved toy-velocipede, partly in section through the stand.

Figure 2 is a top or plan view of the same, the rider being removed.

Similar letters of reference indicate corresponding parts.

My invention has for its object to furnish an improved toy-velocipede; and

It consists in the construction and combination of the various parts of the toy, as hereinafter more fully described.

A is the bottom or foundation of the stand, which is made circular.

B are the sides of the stand, which may be made of tin or other cheap and suitable material, and the lower edge of which is securely attached to the edge of the bottom A.

Upon the upper edge of the sides B is formed, or to it is securely attached an inwardly-projecting flange, C, to serve as a track for the velocipede.

D is an ordinary clock-work, which is attached to the central part of the bottom A of the stand, and which should be provided with a fly-wheel, E, to give steadiness to the movement of the machinery.

The central post *d'* is made hollow, and revolves upon a stationary post, F, the lower end of which is securely attached to the frame of the clock-work, or to the bottom of the stand.

To the upper end of the post F is attached the central part G of the top of the stand, so that the said top G may remain stationary, and thus relieve the clock-work from having to revolve the said top.

The top G should be made of such a size as to leave a narrow circular slot between its outer edge and the inner edge of the flange, or track C.

To the upper end of the sleeve or hollow post *d'* of the clock-work D is attached the inner end of the arm H, which is so formed that its outer end may extend out through the slot between the outer edge of the top G and the inner edge of the flange or track C, without touching either of said parts.

To the outer end of the arm H is detachably attached the lower end of the standard I, the upper end of which is attached to the reach or frame of the velocipede J.

The velocipede J is made similar to the ordinary velocipede, except that the reach should be slightly curved, to correspond with the curve of the track C.

K is the rider, which may be an ordinary doll, secured to the velocipede J, and provided with jointed legs, the feet of which rest upon and are secured to the cranks of the drive-wheel of said velocipede.

By this construction, when the spring of the clock-work has been wound up, the velocipede and rider will be carried around the track with all the movements of the real velocipedist.

The top G may be painted and sanded to represent a circular grass-plat, and the flange or track C may be painted and sanded, to represent a circular gravelled walk around it.

The top G may also be embellished with a flag-staff and flag, if desired.

Having thus described my invention, I claim as new, and desire to secure by Letters Patent—

The improved velocipede-toy, each of its parts being constructed and arranged with respect to the others, in the manner specified.

H. C. ALEXANDER.
